PORTABLE WATER OPERATED ROTARY
CLEANING BRUSH

Edward Haines, Philadelphia, Pa.

Application February 4, 1948, Serial No. 6,132

3 Claims. (Cl. 15—29)

1

This invention relates to water propelled brushes of the type used for polishing, cleaning and the like particularly around the kitchen sink, and in particular a brush in a relatively small unique casing at the end of a handle with a brush provided with an impeller positioned to be rotated by water supplied and returned through the handle.

The purpose of this invention is to provide means for rotating a brush with water supplied from a faucet wherein the brush may be used for cleaning, polishing and the like particularly of silverware, pots, pans, and the like.

Various devices have been provided for rotating brushes and the like by water particularly for commercial uses but these devices are too elaborate and also too costly for domestic and particularly for kitchen use. With this thought in mind this invention contemplates a brush rotatably mounted in a small housing at the end of a handle with water supply and return tubes extending through the housing and handle and with an impeller in the housing in the path of the water so that as water passes through the device it will rotate the brush. The brush also includes valve means actuated by the pressure and controlled by a button on the handle for supplying water to the brush when desired.

The object of this invention is, therefore, to provide means for mounting a brush at the end of a handle where water flowing through the handle will rotate the brush.

Another object of the invention is to provide a water rotated brush head in which the brush may be removed and other attachments used in the head.

Another object of the invention is to provide means in a water actuated brush mounting whereby water may be provided through the mounting to a brush or the like as desired.

A further object of the invention is to provide a water actuated brush or the like for polishing and cleaning particularly in the kitchen which is of a simple and economical construction.

With these and other objects and advantages in view the invention consists of the new and novel combination, construction, and arrangement of parts as hereinafter more fully described, set forth in the claims appended hereto, and disclosed in the accompanying drawings forming part hereof, wherein:

Figure 1 is a view showing a side elevation of the brush unit.

Figure 2 is a plan view of the brush unit with the ends of the water supply and return tubes broken away.

2

Figure 3 is a cross section through the brush head with parts in elevation and parts broken away, taken on line 3—3 of Figure 1.

Figure 4 is a plan view similar to that shown in Figure 2 with the upper part of the handle omitted and with part of the housing broken away and shown in section illustrating the impeller.

Figure 5 is a detail taken on line 5—5 of Figure 3 showing the spring actuated ball valve.

Figure 6 is a cross section through the handle taken on line 6—6 of Figure 1.

Referring now to the drawings wherein like reference characters denote corresponding parts the water driven brush of this invention includes a brush 10 carried by a shaft 11 that is rotatably mounted in a housing 12 and the housing is carried by a handle 13 through a supply connection 14 and a return connection 15.

The brush 10 is provided with a threaded stud 16 that is adapted to be screwed into a socket 17 in the end of the shaft 11 and it will be understood that the brush may readily be removed and other devices or appliances such as scrubbers, bottle cleaners, or polishing devices may be used instead and these devices may be provided with studs similar to the stud 16.

The shaft 11 is provided with vanes 18 and the lower end is rotatably mounted through a bearing 19 in a socket 20 and the upper end 21 is held in a socket 22 in a cover plate 23 of the housing. The socket 20 is provided with a packing gland 24 and the shaft 11 is provided with a pin 25 by which it may be held while screwing a brush or the like into or out of the socket 17 in the lower end thereof.

The housing may be provided with an outwardly flared casing 26 with threads 27 in the upper end by which it is threaded on the threads 28 of the housing as shown in Figure 3. The casing is positioned around the brush and provides a shield therefor.

The base 29 of the housing is provided with a boss 30, as shown in Figure 5, with an opening 31 having a ball 32 held against the lower end thereof by a spring 33, and the spring is held by a nut 34 having an outlet 35 therethrough. As pressure builds up in the housing the ball will be forced away from the seat and water will pass therethrough to the brush.

The supply connection 14 of the housing is connected to a water supply tube 36 through a union 37 and the return connection 15 is connected to a collapsible tube 38, such as a rubber hose, through a union 39, as shown in Figure 4. The tubes 36 and 38 extend through the

handle 13, and the handle is formed with two sections 40 and 41 with the upper section 40 having semi-circular recesses 42 and 43 therein and the lower section 41 having similarly shaped recesses 44 and 45, as shown in Figure 6. The lower section 41 is provided with locating pins 46 and 47, and the sections are secured together by a screw 48 having a head 49 in a recess 50 and with the lower end thereof threaded in a socket 51 in the section 41.

The handle is also provided with a button 52 having a flange 53 on the inner end and the button is positioned in recesses 54 and 55 in the sections 40 and 41 respectively, wherein as the button is pressed inward the tube 38 will be compressed and as the flow of the return water is restricted pressure will be built up in the housing which will compress the spring 33 and open the valve in the base of the housing so that water will drop upon the brush.

With the parts arranged in this manner with the tube 36 connected to a water tap or faucet the water flowing through the tube will rotate the impeller 18 and then return through the tube 38 to the drain. The impeller 18 will rotate the shaft and the brush carried thereby so that the brush may be used for cleaning pots and pans, or bottles and the like, and may also be used for polishing or the like.

It will be understood that modifications may be made in the design and arrangement of the parts without departing from the spirit of the invention.

What is claimed is:

1. A water operated rotary cleaning apparatus comprising a housing, a brush, a casing detachably connected to the housing and in which the brush is positioned, means in the housing rotatably mounting the brush, an impeller positioned in the housing and carried by the brush, a handle, a water supply tube, a compressible water return tube and both of said tubes extending into the handle, water supply and return connections connected to said tubes and communicating with the housing wherein the flow of water through the housing influences the impeller, and the handle being mounted on said tubes so that it overlies the ends of the water supply and return connections, a water pressure responsive valve in the casing, a spring urging said valve into closed position and said valve positioned to drop water upon the brush when the water pressure in the housing overcomes the action of the spring, and a manually operated push button in the handle in engagement with said compressible tube and adapted to be pushed inwardly to compress the compressible tube for restricting the flow of water through the housing to build up the water pressure therein for opening the valve.

2. In a water operated rotary cleaning apparatus the combination, which comprises a housing, a shaft having a threaded socket in the end thereof rotatably mounted in the housing, and projected outwardly of said housing, a brush having a threaded stud threaded in the socket in the end of the shaft outside of the housing, an impeller mounted within said

housing on said shaft, a valve secured to and communicating with the housing, a spring urging said valve into closed position and said valve is positioned so that water passing therethrough drops by gravity on the brush, a handle, a water supply tube, a compressible water returning tube and both of said tubes being positioned in the handle, water supply and return connections connected to said tubes and communicating with the housing wherein flow of water therethrough actuates the impeller, and the handle being positioned on said tubes so that it overlies the ends of the water supply and return connections, and a manually operated push button in the handle in engagement with the compressible tube and adapted to be urged inwardly to compress the tube for restricting the flow of water in the returning connection whereby pressure is built up in the housing to overcome the action of the spring and open the valve to supply water to the brush.

3. In a water operated rotary cleaning apparatus, a housing, a shaft having vanes on one end and a threaded socket in the other end, means rotatably mounting the shaft in the housing with the vanes positioned in the housing and with the ends carrying the threaded socket projecting therefrom, a brush having a threaded stud screwed in said threaded socket, a cylindrical casing threaded on the housing surrounding the brush and having an outwardly flared lower end, a valve in said casing communicating with said housing, a spring urging said valve into closed position, and said valve positioned to drop fluid from the housing onto the brush, inlet and outlet connections extending from the housing and communicating with the housing, supply and return tubes extending from said inlet and outlet connections, a pair of complementary sections positioned over said tubes providing a handle and a button in said handle, adapted to collapse the tube connecting the outlet connections to restrict the flow of fluid therein whereby pressure is built up in the housing to overcome the action of the spring to open the valve and supply fluid to the brush by gravity.
